UNITED STATES PATENT OFFICE.

WILLIAM F. SEMPLE, OF MOUNT VERNON, OHIO.

INHALER.

SPECIFICATION forming part of Letters Patent No. 290,486, dated December 18, 1883.

Application filed September 28, 1883. (No model.)

To all whom it may concern:

Be it known that I, WILLIAM F. SEMPLE, of Mount Vernon, in the county of Knox and State of Ohio, have invented certain new and useful Improvements in Inhalers; and I do hereby declare the following to be a full, clear, and exact description of the invention, such as will enable others skilled in the art to which it pertains to make and use the same.

- 10 My invention relates to improvements in inhalers; and it consists in certain features of construction, and in combination of parts hereinafter described, and pointed out in the claims.
- 15 In the drawings, Figure 1 is a side elevation view of my improved inhaler. Fig. 2 is a side elevation view of the mechanism of the same removed from the container. Fig. 3 is an enlarged section in detail.

- 20 A represents a container, preferably of glass, and of the shape shown.
- B is a cover, and has attached the inhaling-tube b, the tubes C and D, and the stopper B', preferably of cork.
- 25 E is a pendent disk supported from the cover by the tubes C and D, and provided with one or more holes in the central part. The air-tube C passes through the cover and through the disk, and is open from end to end.
- 30 The tube D is closed at the bottom and passes through the cover, and is preferably bent as shown, and is attached at the outer end by the rubber tube d to the part d', known as a "syringe-bulb."

- 35 F is a tube closed at its outer end and branching from the tube D, and has a small jet-orifice, i, on top, just in front of and at right angles to a similar orifice, i', in the end of the bent tube f. These two tubes are preferably soldered together for mutual support, and the latter passes loosely through one of the holes in the disk and extends to near the bottom of the container. This tube is preferably attached to the disk on one side of the hole

through which it passes, to strengthen the 45 parts.

The operation of the device is as follows: The medicine whose fumes it is desired to inhale is placed in the bottom of the container in sufficient quantities to cover the lower end 50 of the tubes f. By compressing the bulb d', air is forced through the connected tubes and discharged through the jet-orifice i, which, by means of the relation of parts shown, will draw the medicine through the tube f and vaporize it 55 in the chamber above the said disk, and from which chamber the patient may inhale the vapor through the tube b.

It will be seen that all of the mechanism is attached to and supported by the cover, and 60 may be removed from the container by removing the cover.

The inhaling-tube b is provided at the outer end with an enlargement or bulb, b', of suitable shape to fit the nostril, so that, when desired, the patient may inhale through the 65 nose.

What I claim is—

1. In an inhaler, the disk E, supported from the cover by the pipes C and D, and provided 70 with an atomizer attached thereto, substantially as shown and described.

2. In an inhaler, the combination, with the pendent disk E, of the tubes F and f, attached to each other and to the disk, and provided 75 with the jet-orifices i and i', substantially as described, and for the purpose specified.

3. In an inhaler, the combination, with the pendent disk E, provided with an atomizer, of the tubes C D d and the bulb d', substantially as and for the purpose set forth.

In testimony whereof I sign this specification, in the presence of two witnesses, this 24th day of September, 1883.

WILLIAM F. SEMPLE.
